MECHANICAL DECOY

Carroll J. Rulison, Baldwinsville, N. Y.

Application February 8, 1944, Serial No. 521,533

6 Claims. (Cl. 43—3)

1

The present invention relates to new and useful improvements in decoys particularly for wild ducks, geese and possibly other fowl, and has for its primary object to provide, in a manner as hereinafter set forth, a device of this character comprising novel means for utilizing the waves or swells of the water in which the device is placed for flapping the wings of said device in a natural, lifelike manner.

Another very important object of the invention is to provide a mechanical decoy of the aforementioned character wherein the head is adapted to turn from side to side in simulation of a live fowl.

Still another very important object of the invention is to provide a decoy of the character described embodying a combination reel and anchor of unique construction for retaining the device and actuating the wings thereof.

Other objects of the invention are to provide an animated decoy of the character set forth which will be comparatively simple in construction, strong, durable, attractive in appearance and which may be manufactured at low cost.

All of the foregoing, and still further objects and advantages of the invention, will become apparent from a study of the following specification, taken in connection with the accompanying drawings, wherein like characters of reference designate corresponding parts throughout the several views, and wherein:

Figure 1 is a view in side elevation, showing a mechanical decoy in accordance with the present invention in use.

Figure 2 is a side elevational view with a portion broken away in section, showing the combination reel and anchor in position in the body of the device.

Figure 3 is a view partially in side elevation and partially in vertical section, showing the decoy in operation with the wings in raised position.

Figure 4 is a view in front elevation of the wings, showing said wings in lowered position.

Figure 5 is a front elevational view, showing the wings in raised position.

Figure 6 is a top plan view of the reel and anchor.

Figure 7 is a view in side elevation of the reel and anchor.

Figure 8 is a bottom plan view of the reel and anchor.

Figure 9 is a plan view of the top plate.

Figure 10 is a view in horizontal section, taken substantially on the line 10—10 of Figure 2.

2

Figure 11 is a perspective view of the housing for the wing-actuating elements.

Figure 12 is a plan view of the hinge plate for the wings with the arms of the wing-actuating elements connected thereto.

Figure 13 is a fragmentary detail sectional view showing the method of mounting the head on the body.

Figure 14 is a fragmentary elevational view showing a contractual detail of a wing-actuating element, and

Figure 15 is a perspective view showing a contractual detail of the wing-actuating element.

Referring now to the drawings in detail, it will be seen that the embodiment of the invention which has been illustrated comprises a body 1 of suitable material. Extending upwardly into the body 1 from the bottom thereof is a longitudinally elongated chamber 2. The walls of the chamber 2 are provided with a lining 3 of suitable metal. The lining 3 includes out-turned flanges 4 which are engaged beneath the bottom of the body 1. The flanges 4 are apertured to accommodate countersunk securing screws 5. Securing screws 6 are also provided in the top 7 of the lining 3. Projecting upwardly from the top 7 of the lining 3 are inverted sockets 8, the purpose of which will be presently set forth.

Mounted transversely in the body 1 and rising from the lining 3 is a substantially segmental housing 9 (Figs. 2, 3, and 11) which is also of suitable metal. Depending from the top 7 of the lining 3 into the chamber 2 is a tubular guide 10 which communicates with the housing 9. A metallic plate 11 of substantially the shape shown to advantage in Figure 9 of the drawings is secured on the upper front portion of the body 1. The plate 11 has formed in its rear portion a transversely elongated opening 12 which communicates with the housing 9. The plate 11 comprises a substantially circular forward end portion 13 having a downturned, toothed peripheral portion 14 which is fixed on the front portion 15 of the body 1.

Fixed on the forward end portion 13 of the plate 11 is a substantially cup-shaped member 16 (see Fig. 13) embodying a circular disc or plate with an upturned peripheral edge flange and depending hub-neck 17. A stationary tube 18 is mounted vertically in the front portion 15 of the body 1 and provides a bearing for the neck 17. The stationary tube 18 terminates, at its lower end, in a substantially oval assembling and retaining enlargement 19 which is closed by the forward end portion of the flange 4.

Journalized for rotation in the stationary tube 18 is a tube 20. A ball thrust bearing 21 supports the lower end of the inner tube 20 on the flange 4. The tube 20 extends above the cup member 16 and has fixed thereon a duck head 22 with a pin 20' through the lower end beneath the lower end of the tube 18 in oval enlargement 19 to keep the head from coming off by being displaced upwardly, as seen in dotted lines in Figure 2 of the drawings. Secured beneath the lower end of the neck of the head 22 is an inverted cup-shaped member 23 which telescopically receives the upstanding cup member 16 and which is rotatable thereon. The member 23 includes an upstanding hub-neck 24 through and beyond which the tube 20 passes and is secured in the upstanding tube or neck 24, as for example by friction, soldering or otherwise, so that the head 22 turns with the tube 20.

Mounted transversely in the tube 20, between the members 16 and 23, is a pin 25 (see Fig. 10). The end portions of the pin 25 are engageable with stops 26 in the cup member 16 for positively limiting swinging movement of the head 22 in opposite directions. It will be observed that the head assembly (parts 23, 24, and 20) is adapted to turn freely, aided by the ball bearing 21.

Mounted longitudinally on the plate 11 and traversing the opening 12 therein is a wing anchoring and hinging plate 27 of substantially the elongated shape shown in Figure 12 of the drawings. Wings 28 are mounted for vertical swinging movement on the plate 27. Cushions or bumpers 29 are provided on the body 1 for the wings 28. Wings 28 are mounted on frames 28' having substantially U-shaped arms 30 of suitable wire, the frames 28' forming out-turned upper ends 30' at the tops of the arms, which out-turned portions 30' are fixed to the wings and hinged to pivotally mount the same on the pivot ears or sleeves of the hinge plate 27. The arms 30 are crossed and said arms are operable in the upper portion of the housing 9 through the opening 12 in the plate 11 on opposite sides of the hinge plate 27. Rubber sleeves 31 are provided on the legs of one of the arms 30 for engagement by the corresponding portions of the other of said arms. Links 32 have one end provided with loops or eyes as shown, pivotally connected or journalized on the bight portions of the substantially U-shaped arms 30. A chain 33, which is operable in the guide 10, is connected at one end to a shackle 32a which engages pivotally with the other ends of the links 32.

The chamber 2 accommodates a removable anchor 34. The anchor 34 includes a relatively heavy base 35 in the form of a metallic plate which conforms substantially to the shape of the chamber 2 in the lower portion of which it is engageable. Rising from the base 35 are posts 36 and 37. Resilient heads 38 are mounted on the upper ends of the posts 36 for snapping engagement in the sockets 8 (see full lines Fig. 3 and dotted line assembly Fig. 2) for releasably securing the anchor 34 in position in the chamber 2. Thumb and finger receiving recesses 39 are provided in the end portions of the base 35 to facilitate removing said base from the chamber 2.

Fixed on the posts 36 and 37 in spaced relation above the base 35 is a substantially diamond-shaped plate 40. The members 35, 36, 37, and 40 constitute a reel on which an anchor line 41 is adapted to be wound.

Mounted for swinging movement on the posts 75

36 is a bail gripper 42 for the line 41. The gripper 42 is formed from a single length of resilient wire which is formed at an intermediate point to provide a coil 43 in which the line 41 is engaged and frictionally secured. The gripper 42 further includes, on its ends, trunnions 44 which are journalized in the posts 36. The base 35 is provided with a centrally located thumb-receiving opening 45 to facilitate winding or unwinding the line 41. An opening 46 in the plate 40 accommodates the guide 10.

One end of the anchor line 41 is connected to one end of a swivel 47. The other end of the swivel 47 is connected by a short line 48 to one end of the chain 33.

It is thought that the operation of the device will be readily apparent from a consideration of the foregoing. Briefly, the approximate depth of the water is ascertained and the anchor 34 is removed from the chamber 2. Enough of the line 41 is unreeled to permit the anchor 34 to rest on the bottom while the body 1 floats on the surface of the water with the wings 28 in lowered position, as illustrated in Figure 1 of the drawings. The line 41 is engaged in the gripper 42 for preventing any more of said line than is needed from being unwound. Now, as the body 1 rises and falls on the waves or swells, the wings 28 are caused to flap or swing upwardly and downwardly by the anchor 34, the line 41, the elements 33, 32, 30, et cetera. Also, the head 22 will be free to swing from side to side in a lifelike manner. If it so happens that the water is not sufficiently rough to actuate the wings 28, this may be manually accomplished by connecting an auxiliary line 41' to the line 48. When the decoy is taken out of the water, the line 41 is rewound on the posts 36 and 37 and the anchor 34 is replaced in the chamber 2 where it is retained by engagement of the heads 38 in the sockets 8. An arrow 49 (see Fig. 8) on the bottom of the base 35 facilitates insertion of the anchor 34 in the chamber 2 in the correct position. Guide slots 50 are provided in the plate 40 for the line 41.

45 It is believed that the many advantages of a mechanical decoy constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

55 1. A decoy of the character described comprising a buoyant body adapted to be supported on the surface of water, wings hingedly mounted on said body, an anchor, means including a line connecting the wings to the anchor for actuation thereby, said line being windable on the anchor, and means for detachably securing the anchor to the body with the line wound thereon.

65 2. A decoy of the character described comprising a buoyant body, wings hingedly mounted on said body, a chamber in the body, an anchor engageable in the chamber, means including a line connecting the wings to the anchor for actuation thereby, means on the anchor for winding the line thereon, and means for releasably securing the anchor in the chamber with the line wound on the second-named means.

70 3. A decoy of the character described comprising a buoyant body, wings hingedly mounted on said body, a chamber in the lower portion of the body, said chamber being open at the bottom of

the body, an anchor engageable in the chamber, coacting head and socket elements on the anchor and in the chamber for releasably securing the anchor in said chamber, means including a line connecting the wings to the anchor for actuation thereby, reel means for the line on the anchor, and a guide for the line in the chamber.

4. A decoy of the character described comprising a buoyant body, wings hingedly mounted on said body, a chamber in the lower portion of the body, sockets in the chamber, an anchor engageable in the chamber, posts on the anchor, means including a line connecting the wings to the anchor for actuation thereby when said anchor is disengaged from the chamber, said line being windable around the posts, and heads on certain of the posts engageable in the sockets for releasably securing the anchor in the chamber.

5. A decoy of the character described comprising a buoyant body, a vertical housing in said body, a chamber in the lower portion of the body

communicating with the housing, said chamber being open at the bottom of the body, wings hingedly mounted on the body, arms fixed on the wings and operable in the housing, links connected to said arms, an anchor engageable in the chamber, means including a line connecting the links to the anchor for actuating the wings, and means for releasably securing the anchor in the chamber, the line being windable on the last-named means.

6. A decoy of the character described comprising a buoyant body, a plate-like member mounted beneath said body, a tube extending vertically through the body, a tubular shaft journaled in said tube, a ball bearing supporting the lower end of the tubular shaft on the plate-like member, a head fixed on the upper end portion of the tubular shaft for horizontal oscillation relative to the body, and means for limiting the movement of said head relative to said body.

CARROLL J. RULISON.
